(57) **CLAIM**

The ornamental design for a modular housing for touch switch, as shown and described.

DESCRIPTION

FIG. 1 is a front, right-side, bottom view of the modular housing for touch switch;

FIG. 2 is a left-side elevational view thereof;

FIG. 3 is a front elevational view thereof;

FIG. 4 is a top-plan view thereof;

FIG. 5 is a bottom-plan view thereof;

FIG. 6 is a right-side elevational view thereof; and,

FIG. 7 is a rear elevational view thereof.

The broken lines depict parts of the housing that form no part of the claimed design.
